Specification for Design.

Patented May 14, 1912.

Application filed April 29, 1909. Serial No. 493,049. Term of patent 14 years.

To all whom it may concern:

Be it known that I, ALBERT A. PAGE, of the town of East Haven, county of New Haven, and State of Connecticut, have invented a new, original, and ornamental Design for a Padlock, of which the following is a specification when taken in connection with the accompanying drawings, which form a part thereof, and in which—

Figure 1 represents a side elevation of a pad lock embodying my new, original and ornamental design, and Fig. 2 represents an edge view of the same.

The design consists of a padlock having in bas-relief on the front of the padlock the representation of a bull dog with full face and closed jaws, mounted above the keyhole and with its front legs spread apart.

What I claim is:—

The ornamental design for a pad lock, as shown and described.
